H. J. DAVIS.
BOTTLE OPENER.
APPLICATION FILED JULY 19, 1917.

Patented Feb. 4, 1919.

Inventor

HENRY JEFFERSON DAVIS

By Watson E. Coleman

Attorney

UNITED STATES PATENT OFFICE.

HENRY JEFFERSON DAVIS, OF WAYNESBORO, GEORGIA.

BOTTLE-OPENER.

1,293,361.

Specification of Letters Patent.

Patented Feb. 4, 1919.

Application filed July 19, 1917. Serial No. 181,554.

To all whom it may concern:

Be it known that I, HENRY JEFFERSON DAVIS, a citizen of the United States, residing at Waynesboro, in the county of Burke and State of Georgia, have invented certain new and useful Improvements in Bottle-Openers, of which the following is a specification, reference being had to the accompanying drawings.

10 This invention relates to means for removing crown corks or like stoppers from bottles.

All devices for removing crown corks known to me are open to the objection that 15 they are liable to engage with the bead or flange at the mouth of the bottle and that in removing the seal or stopper, this flange or bead is liable to be cracked off or a portion of the bottle neck is liable to be cracked off 20 with the bead or flange. There is nothing to prevent the opener from engaging with this bead or flange.

The general object of this invention is to provide a bottle opener for removing crown 25 corks or seals so designed as to eliminate all danger of chipping or cracking off the mouth of the bottle or the adjacent portion of the neck by providing what may be termed a fender engaging with the neck of 30 the bottle and holding the edge which engages the seal away from the flange so that it is impossible for the shoulder or edge which engages with the seal itself or stopper from engaging with the bead at the bottle 35 mouth.

A further object is to provide a device of this character which is very simple in construction, very convenient to use, and which may be cheaply made.

40 Still another object is to provide a form of the device having the characters above described, in which means are provided for centering the bottle relative to the cap engaging edge, so that the bottle cannot be 45 tilted and permit the edge to engage with the bead on the bottle neck.

Still another object is to provide in this 50 form of the device means whereby a simple movement of the bottle inward upon the actuating lever will shift the cap engaging edge upward relative to the bottle and cause it to engage the stopper or cap and remove it.

Other objects will appear in the course of the following description.

My invention is illustrated in the accompanying drawings, wherein:—

Figure 1 is a front elevation of one form of my improved bottle opener;

Fig. 2 is a side elevation thereof with a bottle disposed in operative position;

Fig. 3 is a section on the line 3—3 of Fig. 1;

Fig. 4 is a perspective view of the bottle opener illustrated in Fig. 1, the parts being separated;

Fig. 5 is a front elevation of another and preferred form of bottle opener;

Fig. 6 is a section on the line 6—6 of Fig. 5; and

Fig. 7 is a fragmentary relatively enlarged section showing the manner in which the bottle cap is engaged by the cap engaging edge and illustrating the manner in which the cap is removed.

Referring to Figs. 1 to 3, which show one form of my invention, A designates a counter, wall or other suitable element to which the opening device is attached. The opener in this form comprises a strip of metal which is bent into approximate U form to 80 provide a transverse blade or bar 10 with inwardly projecting side walls 11 and laterally projecting attaching flanges 12, which are perforated for the passage of screws. The bar 10 is less in width than the width of the 85 strip from which this portion of the device is made and above the bar 10 the strip is formed to provide the laterally disposed ears 13, which project out beyond the face of the bar 10. This bar, as will hereafter appear, 90 constitutes the cap engaging edge and a fender.

Disposed between the ears 13 and pivotally mounted thereon is a lever 14, which is formed of a strip of metal bent at its middle 95 to provide two legs 15, these legs being disposed in substantially divergent relation, the extremities of the legs being pivoted to the ears 13 by means of rivets 16 and extending across the legs adjacent the rivets 16 is a 100 cross bar 17. The bottles with which crown caps or seals are ordinarily used are provided at their mouths with the bead 18 and just below this bead, the neck of the bottle is formed with an annular bulbous portion 105 19. Sometimes, however, the bottles are not formed with the bulbous portion 19, or this bulbous portion is irregular so that it is

flatter or less on one side than on another and, therefore, I form the member 10 with a portion 10^b which will engage with the side face of the bottle cap and act as a fender 5 to fend the bottle off so as to prevent the engagement of the edge 10^a with the flange or bead 18.

In the practical use of the device as just described, the bottle is disposed with the 10 bulbous portion 19 against the fender 10, and, as a consequence, the flange or bead 18 is held away from contact with the upper edge 10^a of the transverse web or bar 10, but this upper edge 10^a is engaged with the projecting margin of the cap 20. Upon a depression of the lever 14, the cross bar 17 engages the top of the cap and forces the bottle downward. Inasmuch as the projecting margin of the cap 20 is engaged by the upper edge 10^a of the cross bar 10, it will be obvious that by forcing down upon the bottle, the cap will be disturbed and half of the cap will be forced away from the mouth of the bottle and the bottle be opened. The 20 fender constituted by the bar 10, however, absolutely prevents the beveled edge 10^a from engaging with the bead 18. The part 10^b also acts in the same manner in case the bulged portion 19 of the bottle is either not 25 present or is too flat to be effective. This form of the device requires the use of two hands, because one hand must be used to hold the bottle, while the other hand is used to depress the lever 14.

30 To avoid this objection, I have devised another form of the invention, which is illustrated in Figs. 6 and 7. This form of the device comprises a base 21, which is attached by screws or other instrumentalities to the counter or other element A, this base being 35 provided with two laterally spaced outwardly projecting arms 22. Inward of the ends of these arms, the arms are formed with an integral cross bar 23 corresponding in function to the cross bar 17. The means for 40 engaging the cap comprises a lever designated generally 24 having a relatively long, slightly curved body and at its upper end formed with the upwardly and outwardly 45 projecting laterally spaced arms 25. The lever at its upper end is formed with a transversely extending or widened head 26 to the lateral ends of which the arms 25 are 50 connected or formed and this head is formed 55 to provide a cap engaging edge, which is preferably formed integral with the head. The head constitutes a cap engaging member and a fender and is the equivalent of the member 10 in Fig. 3. The arms 25 are 60 of such length that when the lever is moved back against and into contact with the member A, the edge 27 will be disposed below but inward of the cross bar 23. At its lower end the lever 24 is laterally widened to provide laterally disposed wings 29, which are 65

curved outward and laterally so as to conform to the outward and lateral curvature of a bottle.

It will be seen that the cap engaging edge 27 is formed by notching inward the inner 70 face of the head 26 so as to provide an upwardly and inwardly extending finger 27^a which, like the part 10^b engages with the side face of the cap and fends the bottle off so that the edge 27 will not engage with the 75 bead 18 in case the bulbous portion 19 is not present or is too greatly flattened to be effective. This portion 27^a therefore constitutes a fender.

In the use of this form of the device, the 80 lever normally hangs as in Fig. 7 and when it is desired to move the cap 20, the bottle is disposed against the lever with the cap 20 disposed against the cross bar 23 and then the bottle is forced inward shifting the lever 85 24 inward into the position shown in Fig. 6 and this causes the cap engaging edge 27 to move upward relative to the bottle and forces the cap off. The fender it will be seen bears against the bulbous portion 19 in 90 exactly the same manner as does the web or cross bar 10 and acts as a fender preventing any contact of the upper edge of the blade with the bead 18.

In both forms of my invention, I have 95 provided a fender and a cap engaging edge and means for relatively shifting the bottle and the cap engaging edge so as to force the cap off from the bottle, and it will be noted that in the last referred to form of my 100 mechanism illustrated in Fig. 6, only one hand need be used for operating the opener. It will likewise be seen that many modifications might be made in the form and details of construction of this device, without in any way departing from the principle 105 upon which it is based.

It may be said that a very large number of bottles become chipped, if not actually cracked or broken off at the neck, by the 110 use of the ordinary or usual openers and, as a consequence, these bottles cannot be again used, but have to be thrown aside, because the caps cannot be again placed upon the bottles securely. With my device, however, 115 this is obviated inasmuch as the flange at the mouth of the bottle cannot come in contact with the edge which engages the marginal flange and cap, and a great saving is thus effected.

It will also be noted that in all forms of 120 my invention, there is a member which engages the central portion of the cap and a member which engages the edge of the cap, these two members being relatively movable 125 so that when they are relatively moved, the cap is deformed and its margin pulled upward and away from engagement with the bead so that the cap will be readily detached.

Having described my invention, what I claim is:—

1. A bottle opener including a base having outwardly projecting arms formed with a cap engaging member disposed inward of the ends of the arms, a lever having outwardly and upwardly projecting arms at its upper end pivotally engaged with the extremities of the first named arms, said lever carrying between the arms a member having an upper edge adapted to engage the side edge of a bottle cap, said member constituting a fender engaging with the mouth of the bottle. 35
- 15 2. A bottle opener including a base having outwardly projecting arms formed with a cross bar disposed inward of the ends of the arms, a lever having outwardly and upwardly projecting arms at its upper end pivotally engaged with the extremities of the first named arms, said lever carrying between the arms a member having an upper edge adapted to engage the side edge of a bottle cap, said member constituting a fender engaging with the mouth of the bottle, the lower end of the lever being provided with laterally curved wings constituting means for centering the bottle with relation to the bottle engaging member, the arms on 40 the lever being of such length that when the lever is shifted inward against the supporting element, the cap engaging member 45
- 20
- 25
- 30
- 35
- 40
- 45
- 50
- 55

disposed between the arms will be inward of the cross bar between the arms projecting from the base.

3. A bottle opener including means engaging the central part of a bottle cap, means engageable with the margin of the cap, and means for relatively shifting the said first named cap engaging means whereby to deform the cap, the means engaging with the margin of the cap being formed to provide a fender preventing the engagement of said means with the bead of a bottle mouth.

4. A bottle opener including means engaging the central part of a bottle cap, a member engageable with the margin of a bottle cap, said engaging means and said member being relatively movable, said member having an inner face forming a fender and having an edge engageable beneath the margin of the cap, and a portion above said edge engaging with the peripheral face of the flange of the bottle cap, and means for shifting said member with relation to the first named cap engaging means to deform the cap.

In testimony whereof I hereunto affix my signature in the presence of a witness.

HENRY JEFFERSON DAVIS.
